Primary Examiner—Ian Simmons(74) *Attorney, Agent, or Firm*—Selitto, Behr & Kim**CLAIM**

The ornamental design for a pharmacological inhaler, as shown and described.

DESCRIPTION

FIG. 1 is a perspective view of a pharmacological inhaler showing our new design;

FIG. 2 is a rear elevational view thereof;

FIG. 3 is a front elevational view thereof;

FIG. 4 is a left side elevational view thereof, the right side elevational view being a mirror image of this left side elevational view;

FIG. 5 is a top plan view thereof; and,

FIG. 6 is a bottom plan view thereof.
